[57] CLAIM

The ornamental design for a split ring opening device, as shown and described.

DESCRIPTION

FIG. 1 is a perspective view of a split ring opening device of the claimed design shown from a right-hand perspective; FIG. 2 is a perspective view of the split ring opening device of FIG. 1 shown from a left-hand perspective;

FIG. 3 is front elevational view of the split ring opening device of FIG. 1 of the claimed design;

FIG. 4 is a side elevational view of the right-hand side of the split ring opening device of FIG. 1 of the claimed design; FIG. 5 is a side elevational view of the left-hand side of the split ring opening device of FIG. 1 of the claimed design; FIG. 6 is a bottom end view of the split ring opening device of FIG. 1 of the claimed design; and,

FIG. 7 is a top sectional view of the split ring opening device of FIG. 3. The broken line showings in FIG. 1-7 are for illustrative purposes only and form no part of the claimed design.
